UNITED STATES PATENT OFFICE.

SIDNEY KANEYE, OF FOLEYET, ONTARIO, CANADA.

ROTARY TOOTH-BRUSH.

1,325,498.

Specification of Letters Patent. Patented Dec. 16, 1919.

Application filed September 11, 1918. Serial No. 255,592.

To all whom it may concern:

Be it known that I, SIDNEY KANEYE, a citizen of the Dominion of Canada, residing at Foleyet, in the Province of Ontario and 5 Dominion of Canada, have invented new and useful Improvements in Rotary Tooth-Brushes, of which the following is a specification.

My present invention pertains to rotary 10 tooth brushes of the type in which the brush is rotated first in one direction and then in the other by alternate pressure and relaxation of the hand of the user.

One of the objects of the invention is the 15 provision of a brush of the kind referred to embodying a construction that is susceptible of economic production, and is at the same time reliable in operation and adapted to be actuated with the exercise of but little 20 effort.

Another object of the invention is the provision of a brush comprising a head, bristles, and wire so constructed and relatively arranged that the bristles are joined to the 25 head in a manner calculated to preclude casual displacement of any bristle incidental to the use of the brush.

With the foregoing in mind the invention will be fully understood from the following 30 description and claims when the same are read in connection with the drawings, accompanying and forming part of this specification, in which:

Figure 1 is a longitudinally vertical section of a rotary tooth brush constructed in 35 accordance with my invention.

Fig. 2 is an enlarged longitudinal view of the brush comprised in my improvement.

Fig. 2^a is an enlarged cross section of said 40 brush,

Fig. 3 is a side elevation of the housing of the brush and the tubular shank thereon.

Fig. 4 is a plan of the blank of which said housing is formed,

Fig. 5 is an elevation, partly in section, showing the union through which the shank of the brush housing is connected with the tubular handle of the device.

Fig. 6 is a detail view showing the hand 50 spring of the device.

Fig. 7 is an end view of said hand spring.

Fig. 8 comprises disconnected views of the parts that enter into the gearing housing of the device.

55 Similar numerals of reference designate

corresponding parts in all of the views of the drawings.

The brush proper of my novel device comprises a preferably tubular head 1, bristles 2, and nickel or nickel-plated wires 3; the 60 said brush being produced by laying the wire and bristles on the head, with the bights of the bristles between the wires, after which the wires are twisted and riveted or soldered together at both ends of the head. 65 Manifestly a brush characterized as stated is strong and durable in the respect that there is no liability of any of its bristles being displaced incidental to the use of the brush.

The forward end of the brush head 1 is suitably journaled in the forward end wall of a brush housing 4, formed of the blank shown in Fig. 4. The rear end of the said housing 4 has fixed thereto a tubular shank 75 5, exteriorly threaded at its rear end as indicated by 6. This shank 5 receives the forward tapered portion 7 of the tubular body 8 of the device, and by reference to Fig. 1 it will be noted that the shank 5 is 80 detachably connected to the body 8 through the medium of a ring 9 which is exteriorly threaded as shown in Fig. 5 and is provided with an interior thread to engage the thread 6 of the shank and is also provided with an 85 interior flange 10 adapted to bear against an abutment 10^a on the body 8. By virtue of this construction the housing 4 and its shank 5 may be readily disconnected from the body 8 as when desired to disconnect the 90 head 1 of the brush from the shaft 11 herein-after described. It will also be noted that when the housing 4 is disconnected from the body 8, the brush may be removed from the housing to give place to a new brush. In 95

the present and preferred embodiment of my invention the shaft 11 is journaled in suitable bearings in the longitudinal center of the body 8, and is provided with a reduced forward end, of angle form in cross 100 section, which is socketed in the rear end of the brush head 1. I would also have it understood at this point that by virtue of the union 9 arranged as stated, the brush may be positioned as desired to clean the 105 upper teeth or the lower teeth without involving change in the position of the device in the operating hand of the user; the housing 4 and its shank 5 being simply turned about their axes as occasion demands.

110

Fixedly connected to the rear end of the tubular body 8 is the gearing housing 12 which is preferably, though not necessarily, formed of the parts shown in Fig. 8. In 5 the said housing 12 are disposed the gears 13, 14, and 15; the gear 13 being fixed on the rear end of the shaft 11, and the gears 14 and 15 being fixed, with respect to each other, with the gear 14 intermeshed with 10 the gear 13. In the upper end of the gearing housing is an aperture 16, and working through said aperture is a resilient rack bar 17 which is intermeshed with and is adapted to transmit motion to the gear 15. 15 At 20 is a hand spring, Figs. 6 and 7, which is preferably of concavo convex form in cross section, is provided with a forward loop 21 and has said loop fixed to a saddle 22, of concavo convex form in cross 20 section which saddle is superimposed upon and is riveted to the body 8. The connection of the resilient rack bar 17, to the hand spring 20 is a pivotal one, as shown, and this combined with the auxiliary of the 25 rack bar assures free and easy movement of the back bar and the gear with which it directly coöperates.

In the practical use of my novel brush, the brush after being supplied with water, 30 and tooth powder or with tooth paste is manipulated in the manner common to ordinary tooth brushes—*i. e.*, the brush proper is moved forwardly and backwardly along the teeth and at the same time the hand 35 spring 20 is compressed and released. This compression and relaxation of the spring imparts a multiplicity of rotations to the brush proper with the result that the bristles of said element cleans the inter- 40 dental spaces and in that way prevents discoloration and decay. During the use of the brush, the swivel connection before re-

ferred to permits of the brush proper and its housing being adjusted about their axes so that the brush may be readily placed to 45 the upper or lower teeth or to the inner or outer sides thereof.

The various details of construction shown in the drawings and alluded to herein are not of the essence of my invention and from 50 this it follows that in the future practice of my invention such changes or modifications may be made in matters of construction as fairly fall within the scope of my appended claims. 55

Having described my invention what I claim and desire to secure by Letters Patent is:—

1. The combination in a device of the kind described, of a tubular body, a rotary 60 brush, a housing partially inclosing said brush, a shaft disposed in the tubular body and connected to the brush, means for rotating said shaft, an abutment on the tubular body, and a ring connected with the housing and having a flange opposed to the rear side of the said abutment.

2. In a rotary tooth brush, the combination of a tubular body having a forward tapered portion and an exterior abutment, 70 a housing having a tapered shank receiving the forward portion of the body and also having its rear portion threaded, a ring mounted on the body and opposed to the abutment thereon and threaded to engage 75 the housing shank, a brush mounted in the housing, a shaft mounted in the body, and engaging the brush, a gearing housing fixed to the rear end of the body and receiving the rear portion of the shaft, gearing disposed in said housing, and means for actuating said gearing.

In testimony whereof I affix my signature.
SIDNEY KANEYE.
